United States Patent Office.

WILLIAM HAMILTON, OF TORONTO, CANADA, ASSIGNOR TO HIMSELF AND
HIRAM KIMBALL, OF RANDOLPH, VERMONT.

Letters Patent No. 96,105, dated October 26, 1869.

IMPROVEMENT IN FLUID-METERS.

The Schedule referred to in these Letters Patent and making part of the same.

To all whom it may concern:

Be it known that I, WILLIAM HAMILTON, of Toronto, Canada, have invented a new and improved Meter for Measuring Liquids and Gases; and that the following is a sufficiently full, clear, and exact description of the same to enable one skilled in the art to which my invention appertains, to carry it into effect, reference being had to the accompanying drawings, which form part of this specification.

My meter is provided with a piston and valve-mechanism, which move without appreciable friction or consumption of power. The throw of the valves is instantaneous when the stroke is to be changed, and the apparatus is adapted to operate with uniform accuracy under variations in the pressure and volume of the fluid to be measured.

In the drawings—

Figure 1 represents a longitudinal section of the apparatus in the planes indicated by the line *xx*, fig. 3.

Figure 2, a vertical longitudinal section of the same on the line *yy*, fig. 3.

Figure 3, a vertical transverse section on the line *zz*, figs. 1 and 2.

Figures 4 and 5 are sectional elevations of detached parts of mechanism employed for shifting or reversing the valves.

Figure 6 is an elevation of mechanism employed for converting oscillating or reciprocating rectilinear into intermittent rotary motion to operate the index.

The fluid entering at the port *I*, and following in the course indicated by the arrows in fig. 1, presses against a piston, *A*, mounted upon a guide-rod or rods, *B*.

Annular diaphragms, *C C*, connected to the respective ends of the piston *A*, and to the inside of the cylinder *K*, within which the piston works loosely, serve to separate the ends of the said cylinder, while dispensing with the necessity for packed or frictional surfaces.

It is immaterial whether a single guide-rod is employed, running through and attached rigidly to the piston, and working loosely in chambers in the cylinder heads, or two rods attached rigidly to the respective heads of the cylinder, and entering separate chambers in the ends of the piston.

G G are valves, attached to a valve-rod, *G'*, and employed to place the inlet-port *I* and the discharge-port *H*, respectively, in communication with opposite and alternate ends of the cylinder *K*.

Attached to the piston *A* is a rack, *a*, gearing with a quadrant, *D*, which is keyed to a shaft, *O*.

E represents a weight, mounted upon the upper end of an arm, *E'*, which is fitted loosely on the shaft *O*, but is so connected with the said shaft by means of the clutch-joint represented in fig. 5, or by any other suitable device, as to limit the revolution of the arm

E', independently of the shaft *O*, to an arc of about ninety degrees.

Mounted loosely on the shaft *O* are also a pair of arms, *F F'*, connected rigidly to a hub, *F'*, which forms on each side a knuckle or toggle joint with a rod, *P*, which rods, as each is alternately thrown up from its oblique to its horizontal position by the motion of the connected arms *F F'*, drives the valve-rod *G'* from right to left, or *vice versa*, actuating both valves *G G* simultaneously, and pressing each on to one or the other of its seats with great force.

The drawings show the piston at about half stroke, the weight-arm *E'* having risen forty-five degrees from its horizontal position.

As the piston reaches the end of its stroke, the arm *E'* being carried slightly beyond a vertical position, the weight *E* falls suddenly, and instantaneously shifts the valves so as to throw the respective ports *H* and *I* into communication with the opposite ends of the cylinder *K*. The piston then moves in the opposite direction.

The piston *A* may be made of wood or metal, in the latter case being made hollow, and its interior in communication with the discharging end of the cylinder.

The mechanism *D E E' F P*, and the accessories thereof, also work in the discharging-water.

The weight *E* may preferably be constructed, as represented, with a transverse chamber or cavity, *e*, containing a quantity of quicksilver and water sufficient to fill the remaining space, the object of which is by the flow of the quicksilver back and forth in said chamber on its ends being depressed in the movements of the weight, to render those portions of the movements of said weight, in which it operates the valves, more rapid and powerful, the weight being also thus rendered more sensitive.

The water is to lessen the diminution of the specific gravity of the weight, which would result from the space for the movement of the quicksilver.

The outer end of the oscillating shaft is to be connected with the registering-mechanism by suitable means, a preferred form of which is represented in fig. 6.

A pinion, *L*, is keyed fast to said shaft *O*, and is meshed by a rack, *M*, to one end of which is hinged a pair of ratchet-racks or pawls, *m m*, facing each other, and having their teeth bevelled on opposite sides, which, engaging respectively with opposite sides of a ratchet-wheel or pinion, *N*, on a shaft, *O'*, of the registering-mechanism, impart in the same direction to said shaft the movement resulting from each stroke of the piston as transmitted through the rack *a*, quadrant *D*, and shaft *O*.

The shaft *O' O'* may be connected with the shaft or shafts of one, or a train or series of indexes in any usual or suitable manner.

The lower or both of the pawls *m m* may be pressed

in contact with the ratchet-wheel N, by one or more suitably-applied springs or weights.

The rack proper M is supported in suitable guides.

The registering-motion may be taken from any suitable moving part of the apparatus other than the shaft O, if preferred, and the nature of the converting mechanism modified accordingly. Thus where motion is taken from the piston, the pinion L and rack M may be dispensed with, and a rod projecting longitudinally from the piston take the place of the latter.

It will be observed that the parts in contact with the water are completely balanced by it, and packing is entirely dispensed with.

The apparatus is thus adapted to operate with very slight power or pressure; and its results are positive and absolutely accurate by reason of the instantaneous shifting of the valves at the termination of each stroke of the piston.

Having thus described my invention,

What I claim, and desire to secure by Letters Patent, is—

1. The combination and arrangement, substantially as described, of the balanced reciprocating piston A C C, and balanced valves G G, constructed and oper-

ated substantially in the manner described, for the purpose set forth.

2. The combination, with the valves G G, mounted on a common rod, G', of the oscillating "arms" F F F', constructed and operated substantially as described, for the purpose set forth.

3. In combination with the piston A and the oscillating shaft O, actuated by said piston, the weight E E and arms F F F', constructed and operating substantially in the manner described, for the purpose of instantaneously shifting the valves at the ends of the strokes of the piston, as set forth.

4. In combination with the reciprocating rack M, actuated by the piston, as described, the pawls *m m*, and ratchet-wheel N, employed and operating substantially as and for the purpose set forth.

To the above specification of my new and improved meter for measuring liquids and gases, I have signed my hand, this 14th day of June, A. D. 1869.

WM. HAMILTON.
